UNITED STATES PATENT OFFICE.

JOHN S. FOWLER, OF SAN MATEO, CALIFORNIA, ASSIGNOR TO PACIFIC FOUNDRY COMPANY, OF SAN FRANCISCO, CALIFORNIA, A CORPORATION OF CALIFORNIA.

DRY-PAN CRUSHER.

Application filed December 5, 1925. Serial No. 73,419.

My invention relates to crushing machines of the type known as dry pan machines, and which are principally used for grinding or pulverizing clay in a dry state, for 5 use in making brick, pottery, or other clay products.

The principal object of my invention is to provide an improved screen plate for machines of the described type, which is less 10 subject to breakage than the screen plates now in common use, and which is so constructed that it can be easily replaced, sectionally, when worn, without necessitating the scrapping of the entire plate to eliminate 15 a worn portion of relatively small area.

Other objects and advantages of my invention will be apparent from the following description of a preferred embodiment thereof, which should be read with the understanding that the form, proportion, and 20 arrangement of the several parts of the device may be varied, within the limits of the claims hereto appended, without departing 25 from the spirit of the invention as set forth in said claims.

With this in view a preferred embodiment of my invention will now be described fully with reference to the accompanying drawings, wherein:—

30 Fig. 1 is a part sectional front elevation of the complete machine.

Fig. 2 is a part sectional and partly broken plan view of the revolving pan.

35 Fig. 3 is a plan view, enlarged, of one of my improved screen plate segments.

Fig. 4 is a bottom view of the same.

Fig. 5 is a sectional detail of one of the connections between adjacent screen plate sections.

40 In the drawings, and referring for the moment to Fig. 1 thereof, the reference numeral 1 designates a frame, in the upper portion of which is journaled a horizontal drive shaft 2 provided with means, as for example a pulley 3, for receiving power from an outside source, not shown. The shaft 1 drives, by means of bevel gears 4, a vertical shaft 5, the lower end of which runs in a suitable step bearing indicated 45 at 6. This vertical shaft 5 carries a pan 7, into which the clay or other material is introduced, by any suitable means not shown, and in which said material is ground by rollers 8, there being two such rollers rotatively carried upon a stationary horizon-

tal shaft 9 suitably secured in the frame 1.

The pan 7, as shown in Fig. 2, comprises a hub 10 secured upon the vertical shaft 5, and a frame secured to said hub and made up of radial members 11 and an annular member 12. Upon said frame rests a flat floor comprising a series of sections. The inner portion of said floor, upon which the rollers 8 run, is solid, and is formed of a series of segmental plates 13 resting 60 upon the frame members 11 and 12 and secured thereto by any suitable means, not shown. The outer portion of said floor is perforate, and is formed of a series of segmental screen plates 14, one of which is 65 shown in detail in Figs. 3 and 4. A flange or rim 15, Figs. 1 and 2, extends around the periphery of the pan, and is secured to the ends of the frame arms 11.

An angularly disposed scraper 16, Figs. 75 1 and 2, is adjustably mounted, by means of a suitable bracket 17, upon a fixed bar 18, and overlies the screen plates 14. As the pan revolves, the material is crushed between the rollers 8 and the solid plate portions 13, and is thrown toward the periphery of said pan by centrifugal force. The finer portions of the material drop through the perforations of the screen plates 14 to 80 any suitable place of deposit, not shown, and the remainder is worked back to the rollers 8 by the scraper 16. Thus the grinding is continued until all of the material is fine enough to press through said perforations.

85 The present invention resides in the screen plates 14 and the parts closely associated therewith. As shown in Figs. 2, 3 and 4, I make said plates of a plurality of arcuate concentric sections, there being three such 90 sections, 14^a, 14^b, and 14^c, in the form shown in the drawings, in each segmental plate. Each such section is provided upon its under surface with a marginal flange or rib 19, Fig. 4, adapted to rest upon the pan frame members 11 and 12, and the three sections comprising each segmental plate 95 are preferably connected together by bolts 20 passing through slots 21' in lugs 21 formed at suitable points upon said flanges, as shown in Figs. 4 and 5. To further strengthen the connections between adjacent sections, I prefer to employ a pair of slotted steel plates 22 lying beneath the head and the nut, respectively, of each bolt 20, and the 100 105 110

outer ends of said plates are drawn together by a second bolt 23 to increase the clamping effect produced by the bolt 20. Thus the three sections 14^a, 14^b, and 14^c, are firmly 5 united to form a segmental plate 14, and said plate rests upon the pan arms 11 and is preferably secured thereto by bolts 24, Fig. 2, passing through suitable holes 24', Figs. 3 and 4 in said plate. The surface 10 of the screen plates is preferably flush with the surface of the solid crushing plates 13.

Each arcuate screen plate section is perforated by arcuate slots 25, Figs. 3 and 4, of suitable width. The slots 25, and also 15 the joints 26 between adjacent sections are all concentric with the pan 7, so that, as said pan revolves, any given slot or any given joint will follow a true circular path about the axis of the shaft 5 as a center.

20 The scraper 16 is preferably provided with three removable blades or sections 16^a, 16^b, and 16^c, Figs. 1 and 2, corresponding in position to the three screen plate sections 14^a, 14^b, and 14^c. These blades are preferably independently adjustable, vertically, 25 upon the scraper 16, and are held thereon by any suitable means, not shown in the drawings.

I am aware that screen plates of the 30 described type have been constructed in segmental form, and that such segmental plates have been divided into sections by tangential straight-line joints; and I am also aware that screen plates have been perforated by 35 slots arranged in straight lines, both radially and tangentially. Therefore, my invention resides essentially in the provision of a screen plate divided into sections by arcuate joints concentric with the pan of 40 which they are a part, and perforated by arcuate slots likewise concentric with the pan. This form of screen plate produces important and advantageous results, when used in machines of the described type, over 45 the forms of screen plate now in common use.

One such result is the localization of wear. The surface of screen plates in machines of 50 the type described is subject to wear caused by the abrading action of the material passing under or catching upon the edge of the scraper, and such wear occurs unevenly over 55 the surface of the plate because of the fact that, once a worn area of limited extent appears, the wear in that area proceeds with greater rapidity than in other portions of the plate on account of the relatively greater space between the scraper and the surface of 60 the worn area, and the consequent greater abrading action of the material passing thereunder. However, such worn areas are roughly arcuate in outline, and concentric with the pan. Now if a screen plate segment is not divided into sections, the entire 65 segment must be replaced to eliminate a rela-

tively small worn area; whereas in my arcuate concentric sectional construction, the worn area, in a great majority of cases, is confined to one section, so that that section only need be replaced. Moreover, there is 70 much more likelihood that a worn area will be confined to one section in my arcuate construction in which the segments have the same general configuration as the worn areas, than in the case of segments divided 75 into sections along tangential straight lines.

The arcuate screen plate sections also cooperate with the sectional scraper blades 16^a, 16^b, and 16^c, so that if any one annular series 80 of screen sections wear more rapidly than the others, the scraper blade operating over such worn sections can be adjusted independently of the other blades.

The connections between adjacent screen plate sections, formed by the bolts 20 passing through the slots 21' of the lugs 21, provide for a limited relative adjustment of 85 said sections, so that if one section wears more rapidly than its neighbors, it can be raised slightly to again bring its surface flush with that of the surrounding sections, the slots 21' permitting such relative adjustment. These slotted connections are also useful in permitting adjustment to compensate for slight variations in the thickness 90 of new plates, or to adjust a new section flush with adjacent slightly worn sections. As shown in Fig. 5, the lugs 21 are made long enough to carry the slots 21' without 95 having to make the flange 19 unduly wide.

Another advantageous result of my construction lies in the practical elimination of breakage of screen plates. Such breakage occurs in plates having radial or tangential slots and is caused by a hard lump of material becoming caught or wedged in a slot, and when such a wedged lump is struck by the scraper, a force is set up which has a component at right angles to the length of 100 the bar or band separating the slot in question from the next succeeding slot. Such a force may, and very often does, break the bar, thus necessitating the replacement of 105 the plate or section. In my arcuately and concentrically slotted plate, however, the slots lie along the path of travel of the scraper, instead of across it, so that, when a wedged lump is struck, the force occurs almost entirely in the direction of the length 110 of the slot, and not transversely of the bars. The very slight transverse component due to the angularity of the scraper is not sufficient to cause breakage.

I claim:

1. In a dry pan crusher, a pan comprising 125 a frame; an annular screen plate adapted to rest upon said frame, said plate being divided by radially disposed joints into a plurality of segments, and each segment being divided into sections by arcuate joints con-

centric with the pan; depending marginal flanges formed upon the arcuate edges of each section; and separable connections between the adjacent flanges of the sections of each segment, each connection comprising a bolt extending through the two adjacent flanges, a pair of clamping plates having their upper ends respectively clamped against said flanges by the head and the nut 10 of said bolt, and a second bolt extending through and binding together the lower ends of said plates.

2. In a dry pan crusher, a pan comprising a frame; an annular screen plate adapted to rest upon said frame, said screen plate being divided into a plurality of sections; depending marginal flanges at the edges of and integral with said sections; and means comprising bolts passing through slots in 15 said flanges for separably connecting together said sections, and adapting them for relative vertical adjustment.

3. In a dry pan crusher, a pan comprising a frame; an annular screen plate adapted to rest upon said frame, said screen plate 20

being divided into a plurality of sections; depending marginal flanges at the edges of and integral with said sections; lugs formed with, and longer than the width of, said flanges, said lugs having slots therein; and bolts passing through said slotted lugs for separably connecting together said sections and adapting them for relative vertical adjustment. 25

4. In a dry pan crusher, a pan comprising a frame; an annular screen plate adapted to rest upon said frame, said screen plate being divided into a plurality of sections; depending marginal flanges at the edges of and integral with said sections; bolts passing 30 through slots in said flanges, for separably connecting said sections together and adapting them for relative vertical adjustment, and a pair of clamping plates associated at one end with said bolts and bolted together 35 at their other ends.

In testimony whereof I have signed my name to this specification.

JOHN S. FOWLER.
